UNITED STATES PATENT OFFICE

RAYMOND H. DIETRICH, OF DETROIT, MICHIGAN, ASSIGNOR TO FRANKLIN DEVELOPMENT CORPORATION, OF SYRACUSE, NEW YORK, A CORPORATION OF NEW YORK

DESIGN FOR A MOTOR VEHICLE

Application filed August 15, 1930. Serial No. 36,676. Term of patent 7 years.

To all whom it may concern:

Be it known, that I, RAYMOND H. DIETRICH, a citizen of the United States, residing at Detroit, in the county of Wayne and State of Michigan, and having his post-office address at 826 Fisher Building, Detroit, Michigan, have invented a new, original, and ornamental Design for Motor Vehicle, of which the following is a specification, reference being had to the accompanying drawings, forming part thereof.

I claim:

The ornamental design for a motor vehicle substantially as shown.

In testimony whereof, I have hereunto signed my name, at Syracuse, in the county of Onondaga, and State of New York, this 8th day of August, 1930.

RAYMOND H. DIETRICH.
